& Sease; Mark D. Frederiksen[57] **CLAIM**

The ornamental design for a fence panel, as shown and described.

DESCRIPTION

FIG. 1 is a perspective view of the fence panel showing my new design;

FIG. 2 is a top plan view thereof;

FIG. 3 is a front elevational view there, the rear elevational view being a mirror image thereof;

FIG. 4 is an elevational view taken from the right side of FIG. 3, the left elevational view being a mirror image thereof; and,

FIG. 5 is a bottom plan view thereof.
